UNITED STATES PATENT OFFICE

99,504

DESIGN FOR A GLIDER

Edward S. Goldberg, Philadelphia, Pa.

Application February 13, 1936, Serial No. 61,129

Term of patent 7 years

To all whom it may concern:

Be it known that I, Edward S. Goldberg, a citizen of the United States, and a resident of Philadelphia, county of Philadelphia, State of Pennsylvania, have invented a new, original, and ornamental Design for a Glider, of which the following is a specification, reference being had to the accompanying drawing, forming a part thereof, wherein:

Figure 1 is a perspective view of the article showing my design; and

Figure 2 is an end elevational view thereof.

I claim:

The ornamental design for a glider, as shown.

EDWARD S. GOLDBERG.
